UNITED STATES PATENT OFFICE

HEINRICH EBERHARD, OF BERLIN-FRIEDENAU, GERMANY

VISIBLY INDICATING PIEZO ELECTRIC CRYSTAL RESONATOR

Application filed August 31, 1927, Serial No. 216,675, and in Germany September 2, 1926.

The invention relates to a method for making visible piezo-electric resonance oscillations of crystals, such as quartz, and to the use of such a method in apparatus in which such resonance oscillations are produced by high frequency electric oscillations.

It is a well known fact that under the influence of an electro-magnetic alternating field, especially of a high frequency field many crystals may be excited to oscillations and that such oscillations reach particularly high amplitudes if the crystals are cut in a determined manner with reference to the crystallo-graphic axes, and more particularly also if the electro-magnetic field is arranged in a certain manner with reference to the direction of the crystallo-graphic axes.

Various methods are known for examining and observing such oscillations of a crystal. If, for instance, the crystal is brought into a sufficiently powerful field, microscopically small sparks may, by favourable arrangements, be caused to appear on the surface of the crystal if the conductive coatings which determine the disposition of the field (electrodes) are brought into the immediate proximity of the crystal. This method suffers, however, from the disadvantage that the crystal will easily break as soon as the sparks exceed a certain strength and the tension has become too strong. It has also been suggested that the crystal itself should be arranged in an evacuated or gas-filled vessel. In this manner the oscillation of the crystal may be observed by reason of the luminous phenomena that arise. This method is, however, suitable only if one and the same crystal always remains sealed within the same glass vessel, because with a change of the crystal or a change of the glass vessel the test becomes cumbersome and tedious. This method also has hitherto involved great waste of time in the adjusting of the crystal since, before it was finally sealed in the glass vessel it had previously to be reground, by way of trial, a number of times and to be sealed each time into the glass vessel, before it is of the desired form and dimensions.

I have found that a piezo-electrically act-

ing crystal does not only exhibit luminous phenomena in an evacuated vessel or vessel filled with gas, more particularly rare gas, if the crystal itself is arranged in the vessel, but that such luminous phenomena will also occur if the crystal is situated beside the vessel (i. e. outside the vessel). In that case the luminous phenomena occur only in the neighbourhood of the crystal and may be clearly distinguished from the well known flashing up of a helium tube on its entry into a very powerful, high frequency electric field. The luminous phenomena which form the subject of my invention, will not only occur if the vessel is filled with helium, but also if it is filled with other gases, more particularly rare gases such as neon or argon. They occur, moreover, only with those frequencies in which resonance exists between a natural oscillation of the crystal and the effective oscillation of the electro-magnetic field.

The phenomenon described may according to the object of my invention be employed in order in an electro-magnetic field to excite the luminescence of a crystal whose piezo-electric natural oscillation is to be examined. By observing whether with a stated frequency (to be considered as standard frequency) the luminous phenomenon will occur, I am able to ascertain whether the crystal already possesses the desired natural oscillation and, if necessary, to regrind the crystal accordingly. With variable frequency of the electro-magnetic field we may also ascertain the difference between the standard frequency and that frequency at which the luminous phenomenon may be best seen at the crystal in order from the amount of frequency difference to obtain a measure of the extent to which the crystal should yet be reground. With an apparatus according to the invention these observations may be very easily carried out because according to the invention the crystal is situated outside the gas-filled vessel, the observation of the crystal with such apparatus being therefore also suited for those cases in which the crystal has to be adjusted if after the ad-

justment it is to be arranged in a closed (sealed) glass vessel.

The same apparatus may, if the crystal is employed as standard crystal, be used to ascertain the frequency of a transmitter producing high frequency oscillations and to control the constancy of the frequency. For this purpose I have to observe whether a crystal in the apparatus according to the invention flashes up if the apparatus is fed with the frequency concerned.

If it is not a question of maintaining a transmitter for high frequency oscillations at a certain frequency, but of ascertaining the unknown frequency of a high frequency oscillation, several standard crystals of various known frequencies are arranged in the apparatus according to the invention. Thus, for instance, a number of quartz-pieces may be used which have as natural oscillations the wavelength 100, 125, 150 up to, say, 500 metres. If the apparatus is fed with the frequency to be ascertained, that quartz crystal will flash up which possesses the natural oscillation corresponding to the wavelength. With such apparatus according to the invention already from a distance may be recognized the length of the wave transmitted by observing whether the crystal piece flashing up is situated lower or higher—in a similar manner as with a well-known frequency meter the level of the oscillating reed serves as a measure for the frequency of the oscillation.

For the purpose of adjusting a quartz crystal by means of the apparatus according to the invention it may in certain circumstances be found troublesome that it is not always an easy matter to keep the frequency produced by a transmitter entirely constant, whilst the constancy of a quartz resonator is a very good one. The adjustment of a crystal by means of the apparatus according to my invention may therefore be effected in such a manner that I do not employ a standard frequency but another crystal which serves as standard crystal when the frequencies of the transmitter may alternately be adjusted thus that consecutively the standard crystal and a crystal to be adjusted will flash up. The crystal is properly adjusted if it flashes up at the same frequency at which the standard crystal flashes up. With this adjustment process it is not necessary to ascertain whether the transmitter itself is frequency-constant.

In all these instances it is of considerable advantage if the crystal according to my invention is arranged outside the gas-filled glass vessel and as far as possible in close proximity to the same.

In order that my invention may be best understood I have in the accompanying drawings illustrated by way of example an

embodiment of the apparatus according to the invention:

Fig. 1 shows the connection of an apparatus by means of which the piezo-electrical oscillations may be made visible according to the invention.

Fig. 2 shows the glass vessel employed in connection with it on a somewhat larger scale.

Fig. 3 shows somewhat modified embodiment of such a glass vessel.

In Fig. 1 1 represents the glass vessel which is more plainly shown in Fig. 2. It contains two electrodes 2 which lead a high frequency magnetic field. For this purpose the two electrodes 2 are connected with a coil 3 outside the glass vessel (tube). The coil 3 is coupled inductively across the coil 4 coupled with a transmitter 5 generating high frequency oscillations. 6 shows tuning means, e. g. a variometer for varying the frequency of the transmitter. In the case of a variation of this tuning means 6 a value measuring the frequency generated, for instance, the wavelength of the oscillation produced, may be read off a dial 7. The vessel 1 is filled with a rare gas such as neon and between the two electrodes 2 has a cylindrically shaped cavity 8. This cavity holds a number of quartz crystals 9 all of which are ground in the shape of a rectangle. The quartz pieces 9 are separated from one another by small pieces of non-crystalline material, for example glass tubes 10 so that they cannot mutually influence each other by their piezo-electrically excited oscillations.

Fig. 3 shows a somewhat differently constructed tube 1' of transparent, insulating, non-crystalline material such as glass which, for example, is filled with diluted helium-neon-gas and the inside of which contains only one electrode 2'. On the flat surface or side 8' a crystal 9 is placed. Above such crystal is shown the second electrode 2'' made of a copper wire.

The invention is not restricted to the illustrated embodiment of the tube. Thus, for example, further electrodes may be provided in order to control further circuits by the electric processes in the inside of the tube.

What I claim is:

1. In an apparatus for making visible piezo-electrical resonance oscillations of a crystal a gas-filled vessel, a crystal arranged near said vessel but outside its walls, electrodes arranged inside said gas-filled vessel and provided for applying to said crystal the electromagnetic oscillations which are required to excite the oscillations of said crystal.

2. In an apparatus for making visible piezo-electrical resonance-oscillations of a crystal a gas-filled vessel, several crystals arranged near said vessel but outside its

walls, electrodes arranged inside said gas-filled vessel and provided for applying to said crystals the electromagnetic oscillations which are required to excite the oscillations of said crystals.

5 3. In an apparatus for making visible the piezo-electrical resonance-oscillations of a crystal a gas-filled tube with a cylindrically shaped cavity, several crystals arranged in this cavity of said tube, electrodes arranged inside said gas-filled tube and provided for applying to said crystals the electromagnetic oscillations which are required to excite the oscillations of said crystals.

10 4. In an apparatus for making visible the piezo-electrical resonance-oscillations of a crystal a gas-filled tube with a cylindrically shaped cavity, several crystals arranged in this cavity of said tube, pieces of non-crystalline material interposed between the crystals lying one upon another, electrodes arranged inside said gas-filled tube and provided for applying to said crystals the electromagnetic oscillations of said crystals.

15 5. In an apparatus for making visible the piezo-electrical resonance-oscillations of a crystal a tube with a cylindrically shaped cavity and filled with diluted helium-neon-gas, several crystals arranged in this cavity of said tube, two electrodes arranged inside said gas-filled tube and provided for applying to said crystals the electromagnetic oscillations which are required to excite the oscillations of said crystals.

20 35 In testimony whereof I have affixed my signature.
